[57] CLAIM

The design for the flat-back hexagonal aquarium stand, as shown and described.

DESCRIPTION

FIG. 1 is a perspective view of a flat-back hexagonal aquarium stand showing my new design;

FIG. 2 is a front elevational view thereof;

FIG. 3 is a right side elevational view thereof, the left side being identical in appearance;

FIG. 4 is a rear-elevational view thereof; and

FIG. 5 is a top plan view thereof, the bottom being identical in appearance.

Fig. 1.

Fig. 2.

Fig. 5.

Fig. 3.

Fig. 4.
